UNITED STATES PATENT OFFICE.

MORTIMER L. PACKER, OF COLUMBUS, OHIO.

FUEL-MIXING DEVICE.

1,276,257.

Specification of Letters Patent. Patented Aug. 20, 1918.

Application filed February 18, 1918. Serial No. 217,897.

To all whom it may concern:

Be it known that I, MORTIMER L. PACKER, a citizen of the United States, residing at Columbus, in the county of Franklin and State 5 of Ohio, have invented certain new and useful Improvements in Fuel-Mixing Devices, of which the following is a specification.

This invention relates to fuel mixing devices, and has for its object to provide an 10 improved structure for effecting a thorough mixing of fuel gases prior to their being admitted to points of combustion, and, further, is particularly directed for use in connection with gas burners, whereby the 15 latter will be rendered more efficient from a stand point of heat production and fuel consumption, and to permit of a constant and regulated flame through the provision of improved mechanism which is utilized to 20 supply the burner with a steady and uninterrupted stream of fuel.

It is within the province of the invention to improve generally and to enhance the utility of devices of that type to which the 25 present invention appertains.

With the above and other objects in view, which will appear as the description proceeds, the invention resides in the combination and arrangement of parts, and in the 30 details of construction hereinafter described and claimed, it being understood that changes in the precise embodiment of the invention herein disclosed can be made within the scope of what is claimed without de- 35 parting from the spirit of the invention.

In the accompanying drawing;

Figure 1 is a side elevation of the fuel commingling device comprising the present invention.

40 Fig. 2 is a vertical sectional view thereof.

Fig. 3 is a transverse sectional view taken along the line 2—2 of Fig. 1.

In the accompanying drawing the numeral 1 indicates a fuel supply pipe, which 45 is supported within brackets 2—2, one end of the pipe being closed and the opposite end threaded, as at 3 for connection with a suitable form of valve 4, any preferred means being provided for admitting gas or 50 other similar fuel to the valve 4. In this instance the valve is provided with a plug 5, and is formed with a port 6 for controlling the flow of fuel through the valve structure and into the supply pipe 1. Spaced outlet 55 jets 7 are carried by the outlet pipe, and are formed with centrally disposed, relatively

restricted passageways, through which the fuel flows from the pipe 1 in a thin stream.

Carried by the brackets 2 is a frame 8 which is utilized to support a longitudinally extending, hollow fuel mixing receptacle 9, and the latter is provided with vertically extending inlet tubes 10, which are preferably located in vertical alinement with the jets 7, the lower ends of the tubes 10 being 65 slightly spaced, vertically, from said jets so that gas passing upwardly within the tubes may be mixed with air, drawn into said tubes from the space existing between the jets and the lower ends of said tubes.

The upper ends of the tubes 10 terminate just short from the side of the receptacle 9 opposite to that to which they are connected, so that the gas and air will be permitted to circulate within the hollow interior of the 70 receptacle 9. Located on opposite sides of the tubes 10, and preferably extending in parallel relation therewith, are a plurality of outlet tubes 11, which latter extend into the receptacle and terminate adjacent to 75 that portion of the receptacle through which the tubes 10 are adapted to pass, this construction results in spacing the inner ends of the tubes 10 and 11, so that the same will be relatively offset. The tubes 80 11 are adapted to communicate with any suitable form of gas burner (not shown). It will be understood that any suitable means may be provided for securing the tubes 10 and 11 in fixed positions within the 85 receptacle 9, such as by use of solder or screw threads or the like.

From the foregoing description taken in connection with the accompanying drawing it will be seen that fuel passing through the 90 mixing structure described will be thoroughly commingled with air drawn into the same, so that a highly combustible mixture may be obtained at a gas burner connected with the structure. This is produced by 95 permitting the gas to circulate in a circuitous manner within the receptacle 9, so that the fuel particles will have ample opportunity to become thoroughly commingled before being discharged from the tubes 11. 100 Through the provision of the hollow interior of the receptacle 9, the flow of fuel through the tubes 11 will be effected in a steady and regulated manner, and with total absence of fluctuation or wavering qualities. 105

I claim:

1. A fuel commingling structure for gas

burners, comprising a fuel supply pipe, an outlet opening in said pipe, a mixing receptacle disposed in coöperative relation with said pipe, an inlet member carried by said receptacle and disposed so that one extremity thereof is in substantial alinement with said opening and spaced from the latter while its opposite extremity extends within said receptacle and terminates adjacent the wall of the latter opposite that through which said member enters, and an outlet member having its inner end protruding into said receptacle and spaced a considerable distance beneath the inner extremity of said inlet member whereby a fluid circulating through said receptacle will flow a circuitous path.

2. A fuel commingling structure for gas burners, comprising a fuel supplying ele-

ment, restricted outlet jets protruding from said element, a fuel commingling receptacle, inlet tubular members carried by one side of said receptacle and disposed substantially in alinement with said jets but terminating in spaced relation therefrom, the inner ends of said member extending into the hollow interior of said receptacle and terminating adjacent to that side of the latter opposite to which the tubes enter, and a plurality of outlet members having the inner ends thereof disposed within said receptacle and terminated adjacent to that side of the latter through which the inlet members protrude, whereby a fluid circulating through said receptacle will flow a circuitous path. 35

In testimony whereof I affix my signature.

MORTIMER L. PACKER.

Copies of this patent may be obtained for five cents each, by addressing the "Commissioner of Patents, Washington, D. C."
